UNITED STATES PATENT OFFICE.

ANTOINE DE B. MACKENZIE, OF PHILADELPHIA, PENNSYLVANIA.

DESIGN FOR A HOLDER FOR BRUSHES.

SPECIFICATION forming part of Design No. 26,974, dated April 27, 1897.

Application filed March 18, 1897. Serial No. 628,223. Term of patent 14 years.

To all whom it may concern:

Be it known that I, ANTOINE DE B. MACKENZIE, a citizen of the United States, residing in the city and county of Philadelphia, State of Pennsylvania, have invented and produced a new and original Design for a Holder for Scrubbing and other Brushes, of which the following is a specification, reference being had to the accompanying drawings, forming part thereof.

The leading feature of my design for a holder for a scrubbing or other brush is an attached plating and a socket rising obliquely therefrom.

Figure 1 represents a perspective view of a brush-holder embodying my invention. Fig. 2 represents a vertical section thereof.

In the drawings, A designates the attaching-plate of the holder, and B designates a socket which rises obliquely therefrom.

What I claim is—

The design for a brush-holder, substantially as described and shown.

ANTOINE DE B. MACKENZIE.
